UNITED STATES PATENT OFFICE.

EARL F. CRAFT, OF ST. PAUL, MINNESOTA, ASSIGNOR TO BROWN & BIGELOW, OF ST. PAUL, MINNESOTA, A CORPORATION OF MINNESOTA.

DESIGN FOR AN ASH RECEIVER.

Application filed April 2, 1928. Serial No. 26,093. Term of patent 14 years.

To all whom it may concern:

Be it known that I, EARL F. CRAFT, a citizen of the United States, residing at St. Paul, in the county of Ramsey and State of Minnesota, has invented a new, ornamental, and original Design for Ash Receivers, of which the following is a specification, reference being had to the accompanying drawing, forming part thereof.

Figure 1 is a front perspective view of an ash receiver showing my new design.

Figure 2 is a plan view of the same.

Figure 3 is a side view of the same.

I claim:

The ornamental design for an ash receiver as shown.

EARL F. CRAFT.
